(57) **CLAIM**

The ornamental design for an outdoor drum, as shown and described.

DESCRIPTION

FIG. 1 is a top and front, right side perspective view of an outdoor drum showing our new design according to a first embodiment;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top and front, right side perspective view of an outdoor drum showing our new design according to a second embodiment;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The broken lines in the drawings illustrate portions of the outdoor drum that form no part of the claimed design. The stipple shading in FIGS. 8-14 depicts a contrast of appearance and does not depict any particular color, texture, or material.
